UNITED STATES PATENT OFFICE.

WILLIAM J. CAHILL, OF LENOX, MASSACHUSETTS, ASSIGNOR OF ONE-HALF
TO WILLIAM B. BULL, OF SAME PLACE.

WASH-BASIN, &c.

SPECIFICATION forming part of Letters Patent No. 323,911, dated August 11, 1885.

Application filed May 15, 1885. (No model.)

To all whom it may concern:

Be it known that I, WILLIAM J. CAHILL, a citizen of the United States of America, residing at Lenox, in the county of Berkshire and State of Massachusetts, have invented certain new and useful Improvements in Wash-Basins, &c.; and I hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention consists, primarily, in constructing the bowl, waste-chamber or passage, and waste-passage connecting the bowl and waste-pipe of a wash-basin in one piece; in forming the waste-pipe connecting with such wash-basin or with bath-tubs, water-closets, &c., for a portion of its length with wedge-shaped or tapering ways or sides, to serve as a valve-seat; in a plug-valve having a straight inner face adapted to fit one inner wall of the waste chamber or pipe and close the waste-passage from the bowl or tub, and with wedge-shaped sides to adapt the same to fit the wedge-shaped ways and permit of the unimpeded passage of the overflow from the basin or tub to the outlet-pipe, all as hereinafter described and claimed.

In the drawings, Figure 1 represents a vertical transverse section of a wash-basin, waste, and outlet, with the plug-valve in position therein, the full lines showing the plug-valve in position to seal the waste or passage from the basin, and the dotted lines showing it in raised position to permit of the contents of the basin flowing out therefrom to the waste-pipe. Fig. 2 represents a sectional elevation of a waste-pipe, and Fig. 3 a detail view of the plug-valve, constructed according to my invention.

My present improvement is designed to obviate the necessity of employing the customary stopper and chain in stationary wash-stands and bath-tubs, and the ordinary discharging-valve at the bottom of the water-closet bowls.

In the drawings I have shown my improvement in connection with a stationary wash-

basin. The same principles of construction as there shown are such as would be followed in the construction and arrangement of a water-closet bowl, the plug-valve serving, as in the case of a wash-basin, to retain a supply of water therein, and on the raising of said plug-valve to permit of the automatic discharge of the contents of the bowl. In adapting my improvements to bath-tubs, the tub and waste-passages may be formed integrally, if desired, or the tub formed separately therefrom and provided with a discharge-passage connecting with the waste-pipe, a plug-valve constructed according to my invention being attached to a plunger-rod and sealing such discharge-passage in a similar manner to that shown in the drawings when applied to a wash-basin.

A represents the bowl; B, the rim; C, the outlet or waste passage from the bowl to the waste-pipe, and D the waste pipe or chamber. These parts are molded or cast integrally in any suitable plastic material or metal, as desired.

E represents an overflow-passage connecting the upper part of the basin with the waste chamber or pipe D.

F represents a strainer, which is either removably inserted or cemented or otherwise held in position within the waste-opening in the bottom of the bowl.

G represents my improved plug-valve, which is constructed of solid india-rubber, wood, gutta-percha, papier-maché, or other suitable material, or a combination of two or more of such, and with its side faces of general wedge-shape, except that the side H, which, when the plug is in its lowest position, seals the discharge passage or outlet C from the bowl, is straight, in order to insure said face pressing closely against the inner face of the waste-pipe and securely sealing the outlet C. By thus forming this side H of the plug-valve of perpendicular convex shape, the plug will, as it is raised and lowered, reciprocate in contact with the inner face of the waste-pipe, and as it passes down the perpendicular side H and the tapering sides I of the plug-valve will force any dirt or deposit on the seat down and out of the way.

The top of the plug is usually convex, as shown, to permit of the overflow from the bowl shed-

ding therefrom to the waste-pipe. That portion of the waste-pipe opposite to the bowl-outlet C is usually enlarged, as shown at J, to afford a free passage for the overflow behind 5 the plug-valve when the same is in position to seal the bowl-outlet.

K represents the valve-plunger connected at its lower end to the top of the plug-valve G, for the purpose of reciprocating the same.

10 By making the plunger-valve solid and of wedge shape, as shown, a tight seat therefor can always be assured, as on its being pushed down within the waste-chamber D and along the ways L it will at all times, even after long- 15 continued use, securely bind and be wedged in position, so as to seal the bowl-outlet C, while it can also, owing to its wedge shape, be readily drawn up away from the bowl-outlet to permit of the contents of the bowl discharg- 20 ing into the waste-pipe D.

Having thus described my invention, what I claim is—

1. The combination of a wash or other bowl or tub having a suitable discharge-opening and 25 connecting with the waste-pipe, and an overflow-opening connecting the bowl and waste-pipe at a point above the top of the plug-valve, a waste-pipe, a wedge-shaped plug-valve adapted to fit a portion of the sides of the 30 waste-pipe and partly close the same, and having a perpendicular face adapted to close the bowl-discharge opening, and a plunger connected to the plug-valve, all substantially as and for the purpose set forth.

2. The combination, with a wash-bowl or 35 similar water-reservoir having horizontally-extending discharge and overflow passages connecting with the waste-pipe, the overflow-passage connecting with the waste-pipe at a point above the top of the plug-valve, of a waste-pipe 40 of increased circumference at the part thereof opposite the bowl-discharge opening, and a wedge-shaped plug-valve adapted to partly close the waste-pipe and having a perpendicular inner face and a convex top, and a 45 suitable plunger-rod, substantially as and for the purpose set forth.

3. The combination, with a wash-bowl or 50 similar water-reservoir having suitable discharge and overflow passages connecting with the waste-pipe, the overflow-passage connecting the bowl and waste-pipe entering said waste pipe at a point above the top of the plug-valve, of a waste-pipe having an enlarged portion 55 opposite the bowl-discharge and wedge-shaped ways, and a wedge-shaped plug-valve having a perpendicular inner face, and a suitable plunger-rod, and adapted to partly close the waste-pipe, substantially as and for the purpose set forth.

In testimony whereof I affix my signature in presence of two witnesses.

WILLIAM J. CAHILL.

Witnesses:

WILLIAM B. BULL,
AUGUSTIN REGINER.
